SITZ BATH

Richard J. Perlman, Worcester, Mass., assignor to JMR
Enterprises, Inc., Worcester, Mass.

Filed June 11, 1970, Ser. No. 23,438

Term of patent 14 years

Int. Cl. D23—02

U.S. Cl. D23—51

FIG. 1.

FIG. 2.

FIG. 3.

FIG. 4.

FIG. 5.

FIG. 1 is a perspective view of a sitz bath, showing my new design,

FIG. 2 is an end view of the bath,

FIG. 3 is an opposite end view of the bath,

FIG. 4 is a top plan view of the bath, and

FIG. 5 is a side elevational view of the bath. The other side of the bath appears as a mirror image of the side shown in FIG. 5.

I claim:

The ornamental design for a sitz bath, as shown and described.
